UNITED STATES PATENT OFFICE.

CHARLES L. CASEY, OF CAMBRIDGE, OHIO.

DESIGN FOR A TEAPOT.

42,957.

Specification for Design.

Patented Sept. 3, 1912.

Application filed June 28, 1912. Serial No. 706,499. Term of patent 14 years.

To all whom it may concern:

Be it known that I, CHARLES L. CASEY, a citizen of the United States of America, residing at Cambridge, in the county of Guernsey and State of Ohio, have invented a new, original, and ornamental Design for Teapots, of which the following is a specification, reference being had to the accompanying drawings, forming part thereof.

Figure 1 is a perspective view of a tea-pot,

showing my new design; and Fig. 2 is a plan of the same.

I claim:

The ornamental design for a tea-pot, as shown.

CHARLES L. CASEY.
